ROTARY PUMP

Frederick Kraissl, Jr., North Hackensack, N. J.

Application September 24, 1946, Serial No. 698,907

2 Claims. (Cl. 103—136)

1

This invention relates to improvements in rotary pumps and has for a principal object the provision of a rotary pump in which the main wearing surfaces are floatingly independent of each other and adapted to be removed and replaced manually, thereby enabling the user to remove the worn parts of the pump and replace them with the new ones without having to replace the entire pump per se.

Another object of the invention is the provision in the rotary pump of a rotor having roller slots 120° apart, thereby enabling the pump cylinder to be bored on a true circle. By this arrangement, the urge to rotate the rotor is the same throughout the 360° of rotation, and no "tight place" is encountered as is the case in rotors employing a larger number of blades or rollers.

Yet another object of the invention is the provision in the rotary pump of a shaft, the diameter of which is the same throughout its length, a rotor secured to said shaft and having counterbored portions on each end thereof, rings floatingly positioned in said counterbores, rollers floating in slots formed in said rotor, said rings and said rollers being of such diameters that the sums thereof, when in proper relation, are substantially equal to the bore of the cylinder in which the said rotor, the rollers and said rings rotate, thereby maintaining rolling motion of the rollers against the bore of the cylinder at all times; special advantage being obtained whereby the rollers and rings are caused to revolve continuously, keeping all wear at a minimum.

In order to keep the rolling action of the rollers as even as possible, when they pass the suction and discharge ports, said ports are spanned by V-shaped webs, thereby keeping the pressure substantially constant throughout the length of the rollers and reducing any tendency to skid and thereby obviating uneven wear both on the rollers and in the cylinder bore.

Yet another object of the invention is the provision in a rotary pump of a rotor having a plurality of slots formed therein and replaceable wear plates set into the trailing faces of said slots, said plates being adapted to be removed and replaced after their outer surfaces become worn.

Another object of the invention is the provision in a rotary pump of a shaft which extends from both ends thereof, said shaft being provided with stuffing boxes near each end thereof, and bearing means supported on said pump and engaging the shaft beyond said stuffing boxes.

Other objects and advantages of the invention will be apparent to those skilled in the art upon

2

a study of the following specification, and the accompanying drawings.

In the drawings, which are given merely by way of example to illustrate the invention:

5 Figure 1 is a front elevation of my new and improved rotary pump;

Figure 2 is a sectional elevation of the pump shown in Figure 1;

Figure 3 is a sectional elevation of the pump 10 as seen along the lines 3, 3 of Figure 1;

Figure 4 is a sectional elevation of the pump cylinder alone as seen along the lines 4, 4 of Figure 3, showing the discharge or exhaust port of my new and improved pump; and

15 Figure 5 is a perspective view of the rotor of my new and improved pump, showing one method of mounting the wearing plates in the trailing faces of the slots in said rotor.

Referring first to Figures 1 and 2, my new 20 and improved rotary pump includes a body 10 having a cylinder 11 with flanges 12 and 13 at each end thereof.

Formed integral with the flanges 12 and 13, at 25 the bottom thereof, is a mounting base 14 which may include mounting holes 15.

The cylinder bore is indicated at 16. The cylinder has an inlet boss 17 having an inlet passage 17a formed therein. The cylinder also has an outlet boss 18 and an outlet passage 18a 30 formed therein, as may be seen in Figure 3. The passage 17a communicates with the interior of a swiveled fitting 19 which is secured to the boss 17 by means of a screw 21. The upper end of the fitting 19 may terminate in a flange 19a for connection to any point of use. The passage 18a 35 communicates with the interior of a swiveled fitting 20 which is secured to the boss 18 by means of a screw 22. The inlet passage 17a terminates in the wall of the cylinder to form a port 23, 40 which may be termed the "inlet port." Likewise, the passage 18a terminates in a port 24, which may be termed the "discharge" or "outlet port," and the fitting 20 may be provided with a flange 20a for connection to a point of use.

45 In Figure 4, the discharge port may consist of openings 25, 26, and 27, with webs 28 and 29 therebetween. The combination of the webs 28 and 29 cooperate with the cylinder bore 16 to present additional surface to the rollers (to be presently described) for the purpose of equalizing the wear on these rollers. The inlet port 23 may be formed in the same manner or it may be varied in accordance with the conditions under which the pump is to operate and/or the material which it is to handle.

Turning to Figure 2, the pump is provided with

a shaft 30 which, it will be noted, is preferably the same diameter throughout its length. This eliminates the necessity for stepping the shaft to form shoulders thereon. An end plate 31 has a face 32 which abuts the flange 12 and has formed integral therewith a boss 33. Spaced apart from the boss 33 is a larger boss 34 which is joined to the end plate 31 by means of ribs 34a and 34b. The boss 33 is provided with a bore 33a through which the shaft 30 may pass and concentric therewith is a counterbore 35. At the bottom of the counterbore 35 is a beveled ring 36 which is connected through a passage (not shown) in the end plate 31 to the suction side of the pump, thereby reducing the pressure on the stuffing box to a pressure lower than atmospheric pressure. The stuffing box includes a gland 37 and between the gland 37 and the ring 36 is suitable packing 38. Suitable means is provided for urging the gland 37 to the left, as seen in Fig. 2, but since such means is old in the art, it need not necessarily be shown.

A second end plate 39 is identical with end plate 31. It has a face 40 which seats against the flange 13, and thus the end plates 31 and 39 enclose the cylinder bore 16. The end plate 39 has a boss 41 formed integral therewith and spaced apart from this boss is a second boss 42, which is larger in diameter and which is joined to the end plate 39 by means of ribs 42a and 42b. The boss 41 has a hole 43 therein, through which the shaft 30 extends and this boss has a counterbore 44 to accommodate a stuffing box which may include a ring 45, the beveled inner face of which communicates with the suction side of the pump. Mounted in the counterbore 44 is a gland 46, and suitable packing 47 is employed between the gland 46 and the ring 45.

Secured on the shaft 30 is a rotor 48 which is generally cylindrical in form, as may be seen in Figure 3. The rotor is keyed or otherwise fixed to the shaft and moves therewith.

Formed in the rotor are slots 49, 50 and 51. These slots are substantially 120° apart and the sides of the slots are of such width that rollers 52, 53 and 54 mounted in these slots in the order named, form working fits therewith.

Referring again to Figure 2, the rotor has a counterbore 55 formed therein in one end thereof and a second counterbore 56 formed in the opposite end thereof. Positioned within these counterbores are respectively ring members 57 and 58. These ring members are of such diameter that when the three rollers are in contact with the cylinder bore 16 they may be slipped between the rollers and they function to keep the rollers out near or in contact with the cylinder bore at all times.

From a study of Figure 3, it will be obvious that as the rotor 48 is rotated in a counter-clockwise direction, the fluid medium being handled has just been trapped between the rollers 54 and 52, the bore 16 of the cylinder, and the outer periphery of the rotor between the rollers 54 and 52. As the rotation continues the space described decreases until a point is reached where the roller 52 uncovers the lower edge of the discharge port 24, with the result that further rotation of the rotor causes substantially all of the fluid medium confined within the space defined above to be discharged into the passage 18a via the discharge port 24. By this time, the rollers 54 and 53 have trapped a like volume of the fluid medium and as the rotation continues and

the roller 54 uncovers the port 24, the medium is discharged into the passage 18a. Thereafter, a third volume of fluid medium is trapped between the rollers 53 and 52 and subsequently, this fluid medium will be released into the passage 18a as the roller 53 uncovers the port 24, etc.

In Figure 3, the roller 53 is shown as having traveled its maximum distance into the slot 50. When the roller 54 reaches the bottom of the cylinder bore with its center in line with the center of the cylinder, the roller 54 will have advanced outwardly in the slot, its maximum distance, and as it passes the center and moves to the right (direction of the arrow), it again is moved toward the bottom of its slot.

I have found that by inserting wear plates, such as wear plates 59, 60 and 61 in the trailing faces of the slots 49, 50 and 51, these plates get the brunt of the wear and may consequently be made of material capable of withstanding hard wear. These wear plates are inserted endwise in slots such as the slots shown in Figure 5, wherein the shallow slot 62 is formed in the trailing face of the blade slot 51. The slot 62 has its inner end 63 beveled. Communicating with the slot 62 is a deeper and narrower slot 64. The wear plate 61 has its outer edge 65 conforming to the outer diameter of the rotor. The body 66 of the plate is of such thickness that when the plate is mounted in the slot 62 formed in the face 51a of the blade slot 51, its outer surface is flush with the surface 51a.

Integral with the plate 61 is a portion 67 which is beveled and which cooperates with the beveled groove 63. Also integral with the plate 61 is a tongue portion 68 which forms a working fit in and cooperates with the slot 64. This plate is slid in endwise and is locked in position by the beveled portion 67 and the tongue portion 68, and it cannot get out of the rotor endwise unless an end plate is removed and the rotor is removed from the pump.

Referring again to Figure 2, the boss 34 has a hole 69 formed therein concentric with the shaft 30, and from the outer end the boss 34 has a counterbore 70 formed therein to accommodate the outer race 72 of a ball bearing 71. The ball bearing has an inner race 73 which forms a fit on the shaft 30 and extends beyond the ball bearing to carry a sleeve 74. Threadedly engaging the sleeve 74 is a screw 75, the point of which extends through a clearance hole formed in the extension of the inner race 73.

Likewise, the boss 42 has a hole 76 which is concentric with the shaft 30 and from the outer end, the boss has a counterbore 77 formed therein to accommodate the outer race 79 of ball bearing 78. The inner race 80 of this ball bearing extends beyond the ball bearing to accommodate a sleeve 81. The sleeve 81 has a threaded hole formed therein to accommodate a screw 82 and the point of the screw extends through a clearance hole in the inner race 80 so that the point of the screw may engage the shaft 30.

It will be noted that the holes 69 and 76 are of sufficient diameter to permit the heads of the glands 46 and 37, respectively, to pass therethrough. The end plates 31 and 39 are secured to the pump body by means of screws 83.

The fittings 19 and 20 secured to the pump body by means of screws 21 and 22, respectively, form swivel fits with the pump body and by loosening the screws 21 or 22, either or both of the fittings 75 may be swung to any angle desired, and there-

fore the connection between the inlet and outlet ports and the point of use is facilitated. The pump body, it will be noted, is ribbed to make it very light in weight, and yet substantially strong structurally. A central web 84, Figure 3, joins the cylinder wall and extends down into a horizontal web 85, which may contain the holes 15 for the mounting screws.

Although I have herein shown and described by way of example one embodiment of my new and improved rotary pump, it is obvious that many changes may be made in the arrangements herein shown and described without departing from the spirit of the invention as set forth in the annexed claims.

What is claimed is:

1. In a rotary pump, a body having a cylindrical bore therein and inlet and discharge ports communicating therewith, end plates forming closures therefor, said end plates carrying bearings eccentric to said bore, a shaft mounted in said bearings, a rotor fixed on said shaft and having a plurality of blade slots formed therein, blade means in said first slots adapted to cooperate with said bore; said blade slots having cut-out portions in the form of comparatively radially shallow slots, each having its radially inner edge beveled, and a radially narrower slot extending in the same direction from said blade slot and radially communicating with said shallow slot intermediate its radial inner and outer edges, a hardened and ground wear plate in and forming a working fit with each cut-out portion, each plate having: an outer edge conforming to the outer diameter of the rotor, a beveled inner edge which mates with the inner edge of said shallow slot, and a tongue portion which cooperates with and forms a working fit in the said deeper slot; the blade contacting surfaces of said wear plates also being flush with the side surfaces of said blade slots, and locked against lateral movement by the form of the cut-out portions and maintained therein longitudinally by contact with said end plates when said pump is assembled, said wear plates being removable manually by merely sliding them endwise in said cut-out portions when said pump is disassembled.

2. In a rotary pump, a body having a cylindrical bore therein and inlet and discharge ports communicating therewith, end plates secured to said body and forming closures therefor, said end

plates carrying bearings eccentric to said bore, a shaft mounted in said bearings, a rotor fixed on said shaft and having longitudinal blade slots formed therein, the trailing faces of each blade slot having a second slot formed therein substantially shallower radially than said first slot, said second slot having its radially inner end beveled, a third slot communicating with said second slot extending in the same direction from said blade slot and radially narrower than said second slot, a hardened and ground wear plate of a shape to conform to and adapted to be manually slid into said second and third slots endwise; the face of said wear plate being flush with the face of said first-mentioned slot, the radial outer edge of said wear plate conforming to the outer diameter of said rotor and the inner edge being beveled to match the inner beveled edge of said second slot; said wear plates being retained in said second and third slots by said end plates when said pump is assembled, and blades mounted in said slots and adapted to cooperate with said bore.
